(57) **CLAIM**

The ornamental design for a keypad and keypad housing, as shown.

DESCRIPTION

FIG. 1 is a front perspective view of an embodiment of a keypad and keypad housing as it may appear when mounted on a surface such as a wall (shown by dashed lines); FIG. 2 is a back perspective view of the embodiment shown in FIG. 1;

FIG. 3 is a front view of the embodiment as shown in FIG. 1;

FIG. 4 is a top view of the embodiment shown in FIG. 1 (the bottom view is a mirror image of the top view);

FIG. 5 is a right side view of the embodiment shown in FIG. 1 (the left side view is a mirror image of the right side view); and,

FIG. 6 is a back view of the embodiment as shown in FIG. 2.
